UNITED STATES PATENT OFFICE.

WILLIAM L. BUEDINGEN, OF MILWAUKEE, WISCONSIN.

GAME.

Application filed September 10, 1923. Serial No. 661,977.

To all whom it may concern:

Be it known that I, WILLIAM L. BUEDINGEN, a citizen of the United States, and resident of Milwaukee, in the county of Milwaukee and State of Wisconsin, have invented new and useful Improvements in Games, of which the following is a description, reference being had to the accompanying drawing, which is a part of this specification.

This invention relates to certain new and useful improvements in games and has as a primary object to provide a readily portable game which will be highly amusing to the young and old alike.

It is another object of this invention to provide a game which is self-contained in that it comprises a plurality of sections adapted to be closed to form a unitary parcel when not in use.

This invention has for another object to provide a game comprising a plurality of sections adapted to be closed to provide a unitary parcel when not in use and to be opened to provide a game board or court for the playing of quoits, horseshoes, or any similar game.

It is a further object of this invention to provide a game of the character described comprising two sections adapted to be telescoped when not in use to form a unitary parcel and to be secured end to end to provide a game board or court having a scoring stake pin adjacent opposite ends to which playing members are thrown.

And a still further object of this invention resides in the provision of a section for a game of the character described having a stake or pin rigidly secured therein with its external portions concealed by a cover or wrapping for the section.

With the above and other objects in view which will appear as the description proceeds, my invention resides in the novel construction, combination and arrangement of parts substantially as hereinafter described and more particularly defined by the appended claim, it being understood that such changes in the precise embodiment of the herein disclosed invention may be made as come within the scope of the claim.

In the accompanying drawings, I have illustrated one complete example of the physical embodiment of my invention constructed according to the best mode I have

so far devised for the practical application of the principles thereof, and in which:

Figure 1 is a perspective view illustrating the sections of my game in closed or telescoped condition;

Figure 2 is a perspective view illustrating the sections thereof secured open and secured end to end to provide a game board ready for playing;

Figure 3 is an enlarged fragmentary detail view illustrating the manner of securing the sections end to end, said view being taken through Figure 2 on the plane of the line 3—3, and

Figure 4 is an enlarged fragmentary detail view illustrating the manner of securing the scoring post or pins in the sections, said view being taken through Figure 2 on the plane of the line 4—4.

Referring now more particularly to the accompanying drawing, the numerals 5 and 6 each designate a section having bottom and side walls 7 and 8, respectively, having their exterior provided with a wrapper or cover 9 adapted to have any desired advertising or matter printed thereon.

The sections 5 and 6 are adapted to be telescoped one within the other as illustrated in Figure 1, when the game is not in use, but when it is desired to play the game, the sections are arranged end to end and secured in this position by readily detachable clip members 10. In the present embodiment, the clip members are each struck or formed from a single length or strip of resilient material medially folded to cause the free ends 11 to firmly clamp the abutting end walls of the sections therebetween.

Each section has a stake or pin 12 secured therein, adjacent its outer end, by having its shank passed through an opening in the bottom wall of the section to clamp the section bottom wall between its head 13, and a washer 14 is secured in position by swedging the stake or pin, as at 15. As illustrated in Figure 4, the cover 9 passes over the head 13 to thus conceal it and prevent the marring or scratching of the table or any other support, not shown, upon which the sections may be placed to play the game.

As illustrated in Figure 2, game markers such as a plurality of concentric circles 16 radiate from the axis of each stake or pin 12. The game is played by a plurality of playing members 17 which may be in the

form of miniature horseshoes, quoits, or other form, and the players take positions at opposite ends of the game board or court formed by joining the sections end to end. 5 The members 17 are then pitched toward the stake or pin farthest from the player, the object being to encircle the farthest pin or come as near thereto as possible. The circles are preferably numbered and alter- 10 nately light and dark for convenience in judging the distance of the playing members from the stake or pin.

When the game is over, the clips 10 are removed and placed within one of the sections and the other section then telescoped thereover to provide a unitary parcel capable of being stored without occupying unnecessary space. 15

From the foregoing description taken in 20 connection with the accompanying drawing, it will be readily obvious to those skilled in the art to which an invention of this char-

acter appertains, that I provide a game which is self-contained, may be produced in quantities at a very low cost, and which will 25 be highly interesting to the young and old alike. It will also be obvious that in lieu of the clips 10, the sections may be hingedly connected.

What I claim as my invention is:

A game of the class described comprising a pair of telescopic container sections adapted to form a unitary parcel when not in use, a pin arranged vertically within one end portion of each section and to which playing members are thrown, and said sections adapted to be secured end to end when in use to position the pin of one section a distance from the other, said distance being dependable upon the length of each section. 35

In testimony whereof I affix my signature.

WILLIAM L. BUEDINGEN.
